(Model.)

C. E. KELLOGG,
Picture Frame Easel and Back Rest.

No. 236,953.

Patented Jan. 25, 1881.

UNITED STATES PATENT OFFICE.

CHARLES E. KELLOGG, OF ELMWOOD, CONNECTICUT.

PICTURE-FRAME EASEL AND BACK-REST.

SPECIFICATION forming part of Letters Patent No. 236,953, dated January 25, 1881.

Application filed July 16, 1880. (Model.)

To all whom it may concern:

Be it known that I, CHAS. E. KELLOGG, of Elmwood, in the county of Hartford, State of Connecticut, have invented certain new and useful Improvements in Picture-Frame Easels and Back-Rests, of which the following is a specification, reference being had to the accompanying drawings, where—

Figure 1 is a front view of my invention. 10 Fig. 2 is a back view of the same, the top of the frame being removed. Fig. 3 is a cross-section on line $x-x$ of Fig. 2. Fig. 4 is an enlarged detail section on line $y-y$ of Fig. 2. Fig. 5 illustrates my picture-back rest in its 15 simplest form.

My invention relates particularly to the supporting of small pictures, such as photographs, embellished cards, and the like, and to such pictures as are made on a material not sufficiently strong to act as a proper support to the picture; and the object of my improvements is, first, to provide a picture-back that shall serve to protect the picture it may support from warping or being soiled or destroyed, the said back being sustained in an inclined position by a back-support or brace attached to the same by a new method; second, to combine with such back easel-like standards, which shall give an artistic and pleasing effect; and, third, to provide improved facilities for putting the picture in place in the frame or removing it therefrom.

Referring to the drawings, the letter a represents a frame having a sheet-metal back, c , 35 permanently attached to the easel b , said frame being formed by turning up the edges of the back c into proper shape, so as to contain the picture d and glass front e , as shown in Fig. 3.

40 The base a' may be integral with the back c or with the frame; but, as a matter of cheapness and convenience in manufacture, I prefer to make it from a separate piece that may be properly attached to the back c .

45 The upper portion, a'' , is removable from the main body of the frame for the purpose of introducing the picture. When it is replaced in position on the frame by being sprung on

its grasp is sufficient to securely hold it in place.

Heretofore the brace f has been attached by means of soldering or riveting. To avoid the objections incident to such manner of attachment, I form upon the back c the return-flange c' , and upon the brace the flange f' . This flange f' is then hooked into the flange on the back c , and while in this position the two flanges are firmly closed together, resulting in a secure, durable, and cheap fastening. The back c , on which the return-flange c' is formed, 55 may be of any suitable dimensions, being extended at will by the addition of the easel-like standards, as shown.

In Fig. 5 a simple form of my invention is shown as adapted to the support of pictures 65 without the addition of the frame for glass or the easel-like standards, in which case an additional advantage of the return-flange c' is shown—viz., that it renders the back c more rigid.

70 I claim as my invention—

1. The combination of the picture-back c , having the return-flange c' , with the brace f , having the flange f' hooked into and firmly closed down upon the flange of the back, substantially as shown and described.

2. The combination of the easel b , having the back c , with a return-flange c' , the back being permanently attached to the easel, and having a brace, f , with the flange f' hooked 80 into and firmly closed down upon the flange of the back, substantially as shown and described.

3. The combination of the frame a , having a removable top, a'' , the frame being permanently attached to the easel b and back c , with a return-flange, c' , the back being attached to the easel b , and having the brace f , with the flange f' hooked into and firmly closed down upon the flange of the back, substantially as 85 shown and described.

CHARLES E. KELLOGG.
